(57) **CLAIM**

The ornamental design for a panel for a pet playpen, as shown and described.

DESCRIPTION

FIG. 1 is a front, top and right-side perspective view of a panel for a pet playpen showing our new design;
FIG. 2 is a front view thereof;
FIG. 3 is a rear view thereof;
FIG. 4 is a top view thereof;
FIG. 5 is a bottom view thereof;
FIG. 6 is a right-side view thereof;
FIG. 7 is a left-side view thereof;
FIG. 8 is an enlarged cross-sectional view taken along line 8-8 in FIG. 3;
FIG. 9 is an enlarged cross-sectional view taken along line 9-9 in FIG. 3;
FIG. 10 is an enlarged cross-sectional view taken along line 10-10 in FIG. 3;
FIG. 11 is an enlarged cross-sectional view taken along line 11-11 in FIG. 3; and,
FIG. 12 is a perspective view shown in a state of use and reduced in scale.

The broken lines shown represent the environment of the panel for the pet playpen and form no part of the claimed design.
